UNITED STATES PATENT OFFICE.

HARRY ARONSON, OF ROXBURY, MASSACHUSETTS, ASSIGNOR TO BOSTON SUPERIOR PETTICOAT COMPANY, OF BOSTON, MASSACHUSETTS, A FIRM.

ADJUSTABLE SKIRT.

1,265,870.

Specification of Letters Patent. Patented May 14, 1918.

Application filed May 19, 1914. Serial No. 839,633.

To all whom it may concern:

Be it known that I, HARRY ARONSON, a citizen of the United States, and resident of Roxbury, county of Suffolk, State of Massachusetts, have invented an Improvement in Adjustable Skirts, of which the following description, in connection with the accompanying drawing, is a specification, like characters on the drawing representing like parts.

This invention relates to improvements in skirts in which provision for a certain amount of elasticity in the body of the skirt is made which will permit more freedom in the use thereof and will also prevent the tearing away of the material along the line of stitching of the seams.

In the narrow skirts which are extensively worn at the present time considerable difficulty has been experienced by the tearing of the body portion of the skirt along the seams by reason of the fact that skirts such as silk skirts are made of relatively inelastic material and the lines of stitching which join the adjacent breadths come substantially in line with the warp threads of the fabric so that a slight tension placed upon opposite sides of the seam will cause a separation of the weft threads making a gap which destroys the good appearance of the skirt and will eventually result in the breaking away of the same.

One of the objects of the present invention is to provide elastic seams for the body portion of the skirt connected at the top to a relatively inelastic but adjustable band whereby the skirt is held firmly about the waist of the wearer but is permitted a sufficient amount of yield in its body portion to allow of freedom in walking.

Another object of the invention is to provide an elastic means for connecting the breadths of the relatively inelastic fabric together which will yield upon the stretching of the garment without injuring or bursting the seams.

Other objects of the invention will more fully appear from the following description and the accompanying drawings and will be pointed out in the annexed claims.

In the drawings,

Figure 1 represents a skirt embodying one of the preferred forms of my invention,

Fig. 2 is a back view of the same.

55 The skirt as shown in the drawing com-

prises a waist band 1 of relatively inelastic material which is desirably secured within the binding at the upper portion of the skirt, the body portion consisting of side breadths 2, 3, a front breadth 4 and a plurality of 60 flounces 5 and 6 secured to the bottom of the body portion in the usual manner.

The adjacent edges of the breadths of the body portion are secured together by an insertion 7 of elastic material preferably 65 knitted fabric the edges of which are desirably secured to the edges of the breadths of inelastic fabric by two parallel rows of stitching 8, 9. By thus securing the edges of the elastic portion to the edges of the 70 breadths of the inelastic fabric a strong seam is provided which cannot be broken by tension upon the cloth. As a matter of fact the elastic would ordinarily give way before the 75 seams uniting the same to the inelastic portion break.

The elastic insertions desirably extend from the inelastic waist band to the top 10 of the upper flounce whereby the entire skirt body is made elastic so that it will yield to 80 the action of the knees in walking or in sitting.

The flounce or flounces of the skirt are of inelastic material and may be plaited or gathered in the usual manner being stitched 85 to the bottom of the body portion preferably by two lines of stitching, in this construction therefore the flounces present an inelastic bottom portion depending from the body portion well beneath the knees of the wearer. 90 This construction provides a particularly desirable petticoat for use with narrow skirts which lately have been the mode, the flexible seams of the body portion of the skirt give sufficient elasticity to permit the skirt to 95 yield as the knees and hips are bent in sitting, while the substantially inelastic flounces or bottom portion serve to so limit the step of the wearer that the delicate fabric of the dress which overlies the skirt will not be 100 torn.

In the preferred form of the invention disclosed the skirt is composed of three breadths and the elastic insertion at the back of the skirt extends from the upper 105 edge 10 of the flounce to the bottom of the placket opening.

In order to provide for suitable adjustment of the waist band to fit persons of different size the waist band is desirably 110

provided with a plurality of fastenings such as metal snaps comprising studs 11 secured to the band at one side of the placket and sockets 12 secured to the band at the other side of the placket.

It is to be understood that the embodiment of the invention disclosed herein is illustrative and that the same may be embodied in other forms within the scope 10 thereof.

Having thus described my invention what I claim as new and desire to secure by Letters Patent is:

1. A skirt comprising an inelastic adjustable waist band, a body portion having a plurality of breadths of inelastic material, narrow strips of insertion of relatively elastic material intermediate of and sewed to the adjacent edges of said breadths and extending downwardly throughout substantially the entire length of said body portion and a flounce of inelastic material secured to the bottom of said body portion.

2. A skirt comprising an inelastic waist band, a body portion having a plurality of breadths of inelastic material secured to said waist band and a flounce, strips of insertion of elastic material intermediate of said breadths and extending from the waist band 30 to the flounce and secured at their edges to the adjacent edges of the breadths of said inelastic material by a plurality of rows of stitching.

3. A loose garment, such as a petticoat or skirt, provided with a plurality of gores

united at their longitudinal edges by a yieldable seam structure, said seam-structure being adapted to remain in normal unstretched position throughout the main body of the garment under ordinary conditions, but to absorb shocks due to sudden or abnormal strains and thereby conserve the stitching of said seam-structure, which comprises a transversely elastic strip of material extending between the adjacent margins of the gores and having its edges brought into interlocking relation with the edges of the gores and fastened thereto by rows of stitching.

4. A loose garment, such as a petticoat or skirt, provided with a plurality of gores united at their longitudinal edges by a yieldable seam structure, said seam-structure being adapted to remain in normal unstretched position throughout the main body of the garment under ordinary conditions, but to absorb shocks due to sudden or abnormal strains and thereby conserve the stitching of said seam-structure, which comprises a transversely elastic strip of material extending between the adjacent margins of the gores.

In testimony whereof, I have signed my name to this specification, in the presence of two subscribing witnesses.

HARRY ARONSON.
